UNITED STATES PATENT OFFICE.

WILLIAM J. FRISBIE, OF CHICAGO, ILLINOIS, ASSIGNOR TO JUSTRITE MANUFACTURING COMPANY, OF CHICAGO, ILLINOIS, A CORPORATION OF ILLINOIS.

SPARK-PRODUCING MECHANISM.

1,407,143.

Specification of Letters Patent. Patented Feb. 21, 1922.

Application filed August 29, 1921. Serial No. 496,545.

To all whom it may concern:

Be it known that I, WILLIAM J. FRISBIE, a citizen of the United States, and a resident of Chicago, in the county of Cook, State 5 of Illinois, have invented certain new and useful Improvements in Spark-Producing Mechanism, of which the following is a specification.

My invention relates to spark producing 10 mechanism which is particularly useful as an attachment on the reflectors of miners' acetylene lamps and is of the type in which a serrated friction wheel co-operates with pyrophoric material to produce ignition 15 sparks.

In the device of my invention a spring is connected with the friction wheel and a lever is provided for conveniently rotating the wheel to wind up the spring so that when 20 the lever is released the spring will rapidly rotate the wheel in the opposite direction in association with pyrophoric material to produce a stream of sparks which are directed to the gas outlet of the lamp with 25 which the attachment is associated. The invention covers particularly a more compact and efficient arrangement of the parts, especially the spring, the spring being placed inside of the wheel and between the wheel 30 and the axle around which it rotates.

My improved mechanism is clearly illustrated on the accompanying drawing in which—

Fig. 1 is a front elevational view of a 35 miner's cap lamp with part of the reflector broken away and the sparking attachment applied thereto,

Fig. 2 is an enlarged elevational view of one side of the attachment partly broken 40 away,

Fig. 3 is a similar view of the other side of the attachment partly broken away,

Fig. 4 is an enlarged sectional view on plane 4—4, Fig. 1,

Fig. 5 is an enlarged sectional view on plane 5—5, Fig. 1 and

Fig. 6 is an elevational view of the inside of the wheel operating lever.

The lamp to which I have shown my attachment applied is a miner's cap lamp comprising the water container A, the carbide cup B, the gas tube C, and the reflector D, the valve lever E controlling the flow of

the water to the carbide for the generation of acetylene gas.

55

The sparking device comprises a frame having the base 10 from which extends the threaded sleeve or barrel 11 for receiving the block of pyrophoric material 12 and the spring 13, the cap 14 having threaded engagement with the outside of the sleeve for controlling the compression of the spring and its pressure against the pyrophoric material. Extending outwardly from the base 10 are the two parallel arms 15 and 16 which at their outer ends support the pivot pin or axle 17 which as shown, may be in the form of a tube. A serrated friction wheel 18 has the central opening 19, and secured to this wheel as by rivets 20 is the lever 21 formed of sheet metal, this frame having the opening 22 registering with the opening 19 of the friction wheel. The openings receive the pivot pin 17, and surrounding this pin is the coiled spring 23 which 75 has its one end 24 secured to the lever and its other end 25 anchored to the arm 15. As shown the lever has the slot 26 therein adjacent its hub for receiving the spring end and near the end of the lever is the deflection 27 through which the spring passes, the end 24 of the spring then extending through the opening 28 and being bent around the edge of the lever as clearly shown. At its end the lever has the lateral deflection 29 forming a finger engaging tongue by means of which the lever may be readily swung to rotate the friction wheel. The diameter of the openings 19 and 22 is sufficient to readily receive the coiled spring and to permit the 80 spring to readily expand after having been contracted.

80

When applied to the lamp the sleeve 11 is inserted through the hole 30 in the reflector, the reflector being then clamped 95 between the base 10 and the nut 31 engaging the threaded sleeve. The attachment is positioned with the friction wheel in a diametral plane including the gas orifice of the tube C. The arrangement 100 of the spring is such that the lever will normally be held outwardly with its end against the reflector edge. The pyrophoric material 12 is held against the friction wheel by the spring 13 and when 105 the miner desires to light the lamp he ap-

plies his finger to the tongue 29 and swings the lever inwardly toward the gas tube and then releases it. Swing of the lever causes the spring 23 to be wound up so that upon 5 release it will rapidly rotate the lever and friction wheel in the opposite direction, the engagement of the sharp points or serrations on the wheel with the pyrophoric material then causing the production of sparks which 10 are directed in a stream toward and across the gas outlet of the tube C, and issuing gas is ignited.

The arrangement of the spring 23 within the friction wheel and its operating lever 15 forms a very compact and neat structure. The spring also forms a flexible support for the friction wheel which offsets to a great degree the pressure of the spring 13 on the pyrophoric material. The spring 13 has a 20 tendency to force the pyrophoric material into the teeth of the friction wheel which introduces resistance which will resist turning of the wheel. However, the yielding support of the wheel enables it to extract its 25 teeth from the pyrophoric material to reduce the frictional engagement and to assure rapid rotation thereof by the spring 23 when the lever is released after inward swing thereof.

30 Having described my invention, I claim as follows:

1. In spark producing mechanism of the class described, the combination of a frame, a pin on said frame, a friction wheel having 35 an opening for receiving said pin; a spring surrounding said pin within the wheel opening, said spring being anchored to said wheel and to said frame, means for rotating said wheel against the force of said spring to 40 wind said spring up, sparking material, means for holding said sparking material in range of said wheel, said wound up spring when released causing rapid rotation of said wheel in association with said sparking material to produce sparks.

2. In spark producing mechanism of the class described, the combination of a frame, a friction wheel journaled on said frame, a spring concentric with said wheel and disposed therein, said spring being connected 50 at one end with said frame and at its other end with said wheel, means for rotating said wheel to wind up said spring, pyrophoric material on said frame, said wound up 55 spring when released causing rapid rotation of said wheel in association with said pyrophoric material to produce sparks.

3. In spark producing mechanism of the class described, the combination of a sup- 60 porting frame, a coiled spring supported on said frame, a friction wheel journaled on said spring, said spring being connected at one end with said wheel and at its other end with said frame, means for rotating said 65 wheel to wind up said spring, pyrophoric

material supported on said frame, said spring when released after being wound up causing rapid rotation of said wheel in association with said pyrophoric material to produce sparks.

4. In spark producing mechanism of the class described, the combination of a frame, a pivot pin on said frame, a coiled spring surrounding said pin, a friction wheel surrounding said spring and concentric therewith, one end of said spring being connected with said wheel and the other end thereof being connected with said frame, pyrophoric material supported in said frame in association with said wheel, and means for rotating said wheel to wind up said spring, said spring when released causing rapid rotation of said wheel to co-operate with said pyrophoric material to produce sparks.

5. In spark apparatus of the class de- 85 scribed, the combination of a frame, a friction wheel, a coiled spring supported on said frame within said wheel and said wheel being rotatable around said spring, an operating lever extending from said wheel, one end of said spring being connected with said lever and the other end thereof being connected with said frame, pyrophoric material supported in said frame adjacent said wheel, swing of said lever in one direction causing 90 said spring to be wound up, and release of the lever permitting the wound up spring to rapidly rotate said wheel against the pyrophoric material to produce sparks.

6. In spark producing mechanism of the class described, the combination of a frame, parallel arms extending from said frame, a pin between said arms, a coiled spring surrounding said pin between said arms, a friction wheel between said arms having a central opening for receiving said spring, one end of said spring being connected with said wheel and the other end being connected with said frame, pyrophoric material in said frame, means for holding said material as- 100 sociated with said wheel, said spring being wound up when said wheel is rotated in one direction and when released causing rapid rotation of the wheel in the opposite direc- 105 tion in co-operation with the pyrophoric ma- 110 terial to produce sparks.

7. In spark producing mechanism of the class described, the combination of a frame, parallel walls extending from said frame, a pin extending between said walls, a coiled 120 spring surrounding said pin, a friction wheel between said walls surrounding said spring, a lever secured to and extending from said wheel, one end of said spring being secured to said lever and the other end being secured to said frame, pyrophoric material in said frame, means for holding said pyrophoric material in association with said wheel, ro- 125 tation of said wheel in one direction by said lever causing said spring to be wound up 130

- and said spring operating upon release of the lever to rapidly rotate said wheel in the opposite direction in association with the pyrophoric material to produce sparks.
- 5 8. In spark producing mechanism of the class described, the combination of a frame, parallel arms extending from said frame, a pin extending between said arms, a coiled spring receiving said pin between said arms,
- 10 a friction wheel between said arms having a central opening for receiving said spring, a lever secured to said wheel and extending therefrom, one end of said spring being secured to said frame and the other end there-
15 of being secured to said lever, said lever hav-
- ing a slot in which the spring end is disposed, pyrophoric material in said frame, means for holding said material in operative association with said wheel, rotation of said wheel by said lever in one direction causing 20 said spring to be wound up, said wound up spring when released causing rapid rotation of said wheel in the opposite direction in engagement with the pyrophoric material to produce sparks.
- 25

In witness whereof, I hereunto subscribe my name this 26th day of August, A. D. 1921.

WILLIAM J. FRISBIE.
